Primary Examiner — Ian Simmons*Assistant Examiner* — Mark Cavanna(74) *Attorney, Agent, or Firm* — Symbus Law Group, LLC; Clifford D. Hyra(57) **CLAIM**

The ornamental design for a medical diagnostic device, as shown and described.

DESCRIPTION

FIG. 1 is a top, front and left side perspective view of a medical diagnostic device.

FIG. 2 is a left side view thereof.

FIG. 3 is a right side view thereof.

FIG. 4 is a top view thereof.

FIG. 5 is a bottom view thereof.

FIG. 6 is a rear view thereof.

FIG. 7 is a front view thereof; and,

FIG. 8 is a detail view thereof.

The broken lines are a boundary line indicating the edges of the detail view and form no part of the claimed design.

1 Claim, 6 Drawing Sheets---
